DESIGN FOR A PIN OR SIMILAR ARTICLE

Arthur Gerald Leary, Mount Vernon, N. Y.

Application December 8, 1943, Serial No. 111,951

Term of patent 3½ years

(Cl. D45—19)

To all whom it may concern:

Be it known that I, Arthur Gerald Leary, a citizen of Great Britain, residing at Mount Vernon, in the county of Westchester and State of New York, have invented a new, original, and ornamental Design for a Pin or Similar Article, of which the following is a specification, reference being had to the accompanying drawing, forming part thereof.

Fig. 1 is a face view of the pin or similar article showing my new design; and

Fig. 2 is an edge view of the pin or similar article.

I claim:

The ornamental design for a pin or similar article, substantially as shown.

ARTHUR GERALD LEARY.
